Primary Examiner — Wan Laymon

(57) **CLAIM**
The ornamental design for a pico projector with a pop-up connector, as shown and described.

DESCRIPTION

FIG. 1 is a front isometric view of the projector with the pop-up connector in an operational configuration.

FIG. 2 is a top view of the projector with the pop-up connector in the operational configuration.

FIG. 3 is a bottom view of the projector with the pop-up connector in the operational configuration.

FIG. 4 is a left side view of the projector with the pop-up connector in the operational configuration.

FIG. 5 is a right side view of the projector with the pop-up connector in the operational configuration.

FIG. 6 is a first end view of the projector with the pop-up connector in the operational configuration.

FIG. 7 is a second end view of the projector with the pop-up connector in the operational configuration.

FIG. 8 is a front isometric view of the projector with the pop-up connector in a non-operational configuration.

FIG. 9 is a top view of the projector with the pop-up connector in the non-operational configuration.

FIG. 10 is a bottom view of the projector with the pop-up connector in the non-operational configuration.

FIG. 11 is a left side view of the projector with the pop-up connector in the non-operational configuration.

FIG. 12 is a right side view of the projector with the pop-up connector in the non-operational configuration.

FIG. 13 is a first end view of the projector with the pop-up connector in the non-operational configuration; and,

FIG. 14 is a second end view of the projector with the pop-up connector in the non-operational configuration.

The broken lines immediately adjacent to the claimed areas represent the bounds of the claimed design while all other broken lines showing fasteners and a male connector configured for electrically connecting the projector to a cell phone or portable media device represent environment and are for illustrative purposes only; the broken lines form no part of the claimed design.
